WILLIAM. GORMAN.

—ASSIGNOR TO—

RUSSELL AND ERWIN MFG. CO.

DESIGN FOR DOOR
EGGUTCHEON

PATENTED
AUG 17 1869

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,615, dated August 17, 1869.

DESIGN FOR A DOOR-ESCUTCHEON.

The Schedule referred to in these Letters Patent and making part of the same.

To all whom it may concern:

Be it known that I, WILLIAM GORMAN, of New Britain, in the county of Hartford, and State of Connecticut, have originated and designed a new Design for Door-Escutcheon; and I do hereby declare that the following is a full, clear, and exact description thereof, reference being had to the accompanying drawing, making a part of this specification.

In the accompanying drawing a design is exhibited for an ornamental escutcheon, which is, in its character, a combination of the Persian and Grecian styles of ornamentation.

A raised moulding, *a*, surrounds the edge, which is

intersected by four leaves, *A*, radiating from the circular depression *B*, which receives the knob-escutcheon.

The ground is matted work, relieved by raised ornamental designs, in harmony with the style adopted.

What I claim as my invention, and desire to secure by Letters Patent, is—

The ornamental design for a door-escutcheon, substantially as described, and shown in the drawing.

WILLIAM GORMAN.
